UNITED STATES PATENT OFFICE

JAKOB SCHMIDT, OF NEWARK, NEW JERSEY

DESIGN FOR A COMBINATION RADIO AND CLOCK CABINET WITH FOUNTAIN

Application filed April 1, 1932. Serial No. 43,359. Term of patent 7 years.

To all whom it may concern:

Be it known that I, JAKOB SCHMIDT, a citizen of the German Republic, residing at Newark, in the county of Essex and State of New Jersey, have invented a new and original and ornamental Design for a Combination Radio and Clock Cabinet with Fountain, of which the following is a specification, reference being had to the accompanying drawings, forming part thereof.

Fig. 1 is a front elevational view and Fig. 2 a side elevational view of my combination radio and clock cabinet with fountain.

I claim:

The ornamental design for a combination radio and clock cabinet with fountain substantially as shown.

JAKOB SCHMIDT.
